PROCESS AND APPARATUS FOR REFINING
MINERAL OILSWilbur G. Laird, New York, N. Y., assignor to
Heat Treating Company, New York, N. Y., a
corporation of Delaware

Application April 4, 1927. Serial No. 180,728

10 Claims. (Cl. 196—69)

This invention relates to a process and apparatus for refining mineral oils, more particularly to the art of converting crude or other mineral oil products into gasoline like material.

5 The present invention is an improvement on the well known tube and drum oil cracking systems in which oil to be cracked is passed under pressure through a highly heated coil mounted in a furnace, then into a large drum or still where 10 the oil remains for a considerable time in order to allow the cracking reaction to complete itself.

Probably the most outstanding disadvantage met with in the use of such cracking systems is the accumulation of carbon in the drum and 15 often in the dephlegmator which is used to extract the heavier products from the vapors leaving the reaction chamber. This carbon or coke accumulation must be removed at very frequent intervals, which necessitates the shut down of 20 the apparatus with subsequent cooling before the workmen can remove the hardened carbon from the drum with pick and shovel or before boring or other devices can be used to remove the same.

In the use of the usual systems and operating 25 methods the principal loss resulting from the accumulation of carbon is the time lost in cooling the apparatus so that the carbon can be removed and that lost in starting up the apparatus again. Time consumed in these operations 30 cuts down the production of the apparatus, while the operating cost increases. If it is assumed for example that the cracking apparatus must be shut down for several days each month to remove carbon the decrease in production will be from 35 10 to 25%, which if avoided would result in a substantially equal profit because the operating costs continue just the same.

Another defect in present apparatuses and 40 mode of operating the same is that where carbon is continuously allowed to accumulate in the cracking drum the available storage for hot oil becomes less and less so that the time allowed for the cracking reaction becomes shorter as the 45 run continues.

In present systems also the cracking operation 50 is allowed to extend into the dephlegmator which is commonly used to receive vapors from the cracking or reaction drum. This is particularly true after a certain amount of carbon, pitch and tar is allowed to collect in the reaction drum. Cracking in the dephlegmator naturally produces 55 carbon, etc., which cakes on the metal surfaces or is returned to the heating furnace with the reflux condensate and thereby promotes the ac-

cumulation of carbon and coke in the furnace tubes.

Wherefore the present invention has for its object:

The provision of a process and apparatus 60 wherein the various disadvantages enumerated above are overcome:

The provision of an apparatus adapted to carry out the novel process pointed out hereinafter;

The provision of an apparatus adapted to operate continuously at high temperatures and pressures;

The provision of an oil cracking apparatus 70 adapted to provide a constant storage capacity for the oil undergoing cracking;

To provide a continuous process for the cracking of mineral oils as distinguished from processes in which it is necessary to shut down to remove carbon;

To provide a cracking process in which a constant volume of oil may be maintained in the cracking zone; and,

To provide a process for cracking mineral oils in which the cracking of the oil is restricted to 80 the reaction zone and not allowed to go on in the dephlegmator.

These and other objects will be apparent from the following detailed description taken in connection with the accompanying drawing in which:—

The figure is a diagrammatic elevational view 85 partly in section of an apparatus in accordance with the invention and in which the novel process may be carried out.

Referring to the drawing the oil to be cracked 90 and which may be a mineral oil of any type such as an asphaltic or paraffin base crude oil, distillate or residuum, shale oil, oils resulting from the distillation of coal or a mixture of any of these oils, is introduced into the apparatus through 95 the pipe 2 by any convenient means such as a pump (not shown). The oil thus introduced passes downward through a series of heat inter-changers 4, mounted on a dephlegmating and rectifying tower 6, leaving the lowermost ex- 100 changer by the pipe 8. The details of construction of this tower are described in a pending application, Serial No. 125,893, filed July 30, 1926. For present purposes it will be sufficient to point out that the oil in the heat exchangers 4 105 passes in heat exchange but out of contact with vapors from a cracking chamber described later.

The pipe 8 discharges into a tank 10 from 110 which the preheated oil passes by a valved pipe 12 to a tubular cracking furnace 14, where the oil

is heated to or above the cracking temperature under pressure. This furnace heater may be of any of the conventional pipe still furnace types. The highly heated oil leaves the heater 14 by a 5 valved pipe 16, by which it enters one end of a horizontally placed rotatable reaction chamber 18 in which a considerable body of oil is maintained and in which the cracking operation is allowed to take place.

10 The reaction chamber 18 may be mounted for rotation in any convenient manner; as shown it is mounted on two sets of spaced rollers 20 which are supported by suitable bearings and foundation work (not shown). The chamber 18 may be 15 rotated by the gear and shaft mechanism 22 when connected to any available source of power. In order to make proper connections with inlet and outlet pipes the ends of the chamber 18 are provided with central stuffing boxes 24. At the 20 inlet end the pipe 16 connects through a T with a perforated distributor pipe 26 which extends through the stuffing box 24 and into the chamber 18 a considerable distance. At the opposite end of the chamber a vapor outlet pipe 28, arranged 25 as shown, to extend above the liquid level in the chamber 18, passes through the stuffing box 24 at the outlet end of the chamber. Within the chamber is placed a number of metal balls 30, which, as the chamber rotates, keep the carbon 30 formed and deposited in the cracking operation from accumulating on the walls.

From the rotatable reaction chamber 18 the vapors pass by the offtake 28 which is connected to a valved vapor pipe 32 discharging into a chamber 34 forming the base of the tower 6. This chamber may or may not be constructed integral with the dephlegmating tower, but for convenience is shown so constructed. The vapors entering the compartment or chamber 34 are 35 at a comparatively high temperature and if delivered to a dephlegmator would probably continue to crack and thus deposit carbon. In order to obviate this effect and to avoid the necessity of extensive condensing apparatus to handle the vapors, relatively cool oil (charging stock) is 40 sprayed into the chamber 34 from a distributor 36 above the entering vapors. Oil is supplied to this distributor through a valved pipe 38 which connects with the tank 10. Vapors with their 45 temperature reduced below the cracking point leave the chamber 34 by an offtake 40 which consists of an open ended pipe extending through and above a partition plate 42 which forms the 50 upper part of compartment 34. These vapors then pass through a series of alternately placed 55 bubble cap trays 44 and heat interchangers 4, so that they alternately pass through condensate maintained on the trays and in heat exchange with charging stock passing through the ex- 60 changers 4. During the passage of the vapors through these various condensing and rectifying stages in the tower 6 the condensate produced in the units 4 flows counter to the vapors back onto the bubble cap tray next below, while the 65 condensate on the trays passes by conventional overflow pipes onto the next bubble tray below and from the lowermost tray into the condensate trap formed by the pipe 40 on the partition 42. Between each bubble tray in the tower is placed 70 a dead plate 46 which causes vapors to pass through suitable openings (not shown) into the heat exchangers 4, from which the vapors not condensed pass by other openings into the space below the bubble tray next above.

75 While the condensate collecting on the parti-

tion 42 has a temperature considerably above that of the end point of gasoline it nevertheless contains absorbed gasoline (2 to 4%) which may be stripped therefrom by bubbling a gas through the condensate. This is accomplished by means of a gas distributor 48 mounted above the partition 42, gas being supplied hot or cold as desired from any suitable source by the valved pipe 50. Stripped condensate is withdrawn by a pump 52 through a pipe 54 and introduced into the advancing charging stock in one of the exchangers 4 by a pipe 56. The invention is not limited to the particular point at which the reflux condensate is mixed with the charging stock, since such mixing may be made in any of the exchangers 4, the tank 10 or line 12 as desired. It is preferred to maintain a considerable body of condensate on the partition 42 in order to secure effective stripping of the gasoline therefrom. This may advantageously be accomplished by controlling the speed and operation (starting and stopping) of the pump 52 by an automatic device controlled in turn by the level of the liquid condensate in the chamber above the plate 42.

80 The vapors and gases remaining uncondensed in the tower 6 are conducted by a valved pipe 58 to a condenser 60 which may be cooled by water or by cold charging stock before it enters the exchangers on the tower 6. The condensate 85 thus produced together with fixed or non-condensed gases pass by a valved pipe 62 to a trap 64 from which the condensed product is drawn by a valved pipe 66 and the gases by a pipe 68. The fixed gases may be scrubbed and sent to 90 storage by a valved pipe 70 or a portion of them (scrubbed or not) may be mixed with the charging stock by means of a booster 72 and pipe 74 which connects with the charging line 2.

95 In the operation of the apparatus a body of oil 115 is accumulated and maintained in the reaction drum 18 to a level slightly above the axis so that the oil and vapors from the pipe still 14 are distributed into such body by the distributor pipe 26. This body of oil, from the very nature of the 120 process, consists of a mixture of hydrocarbons (including absorbed gasoline), polymers, etc., tar, pitch, coke and carbon. Because of the tendency of the tars and carbon to settle out of the mixture (even when the chamber 18 is rotated) provision is made for taking off the cleaner material by a valved draw off pipe 76 which passes centrally through the vapor offtake 28 and discharges directly into the compartment 34. The heavier material including the carbon and pitch 125 in suspension is withdrawn by a similar valved pipe 78 centrally placed in the opposite end of the chamber 18, this pipe however being bent downward inside the chamber so as to draw oil from the bottom thereof. Oil and carbon withdrawn by the pipe 78 are discharged into a stripper or concentrating still 80 where the lighter products are distilled therefrom by introducing a gas through a gas distributor 82 mounted in the bottom of this still. The distillation is carried out at the same pressure as that used in the cracking still 18 so that the vapors evolved may be delivered either by a valved pipe 84 (by means of an aspirator) into the transfer line 16 or by a valved pipe 86 into the vapor line 32.

130 140 145 Which pipe to use will largely depend on the temperature of the vapors leaving the stripper 80 and/or the viscosity of the oil in the chamber 18 which should be maintained below the saturation point of the tarry matter therein. The 150

distillation in the still 30 is preferably carried to the extent of leaving only oil of the fuel oil type together with the suspended carbon, tar, pitch, etc., this mixture being withdrawn through 5 a valve pipe 88 into a cooler 90 from which the cooled mixture is passed to a thickener 92 by a pipe 94. The oil-carbon mixture enters at the top and near the center of the thickener, which by proper operation produces a rapid separation 10 of the oil from the carbon, the oil overflowing into a trough 96 from which it is drained by a valved pipe 98, while the carbon is discharged at the bottom through a pipe 100 by the aid of a steam or gas jet from a pipe 102. The oil delivered by 15 the pipe 98 may be reintroduced into the feed line at any point or may be used in the chamber 18 to carry out more carbon, etc., but it is usually too heavy for these purposes and is preferably used as fuel oil.

20 The relatively clean oil delivered to the chamber 34 from the cracking vessel 18 mingles with the oil sprayed from the distributor 36 and the condensate produced thereby. This mixture contains an appreciable amount of absorbed gaso- 25 line hydrocarbons which are stripped therefrom by introducing a gas through a gas distributor 104 mounted at the bottom of the still or chamber 34. The stripped oil is withdrawn through a valved pipe 106 by a pump 108 and passed 30 through a pipe 110 into the feed line 12. At the junction of the pipe 110 with the feed line 12 is an injector device 111 by which the oil driven under pressure by the pump 108 may be utilized to draw oil from the chamber 10. Gas from the 35 booster 72 may also be used in the injector 111 for forcing the oil through the heater. It is preferred to maintain a substantial body of oil above the distributor in chamber 34, which may be done automatically in the manner referred to above 40 in connection with the oil level maintained above the partition 42.

The use of a gas, particularly the non-condensed gas from the final condenser, with the feed oil is especially desirable when such stock as gas 45 oil is used for cracking, due to the fact that a lower vaporizing temperature is secured in the heat interchangers 4 where heat of condensation of vapors from the still may be directly transferred to heat of vaporization of the charging 50 oil. Where, however, it is desirable to maintain a strictly liquid phase of the charging oil the gas circuit may be omitted.

In carrying out the process the operation is rendered continuous by the use of the "ball mill" 55 type reaction drum 18 in such a manner as to keep the carbon and coke, formed by cracking of the oil, in a fine state of subdivision so that it may be removed with the oil withdrawn by pipe 78. The balls 30 which may be made of iron 60 or steel should be sufficiently large and heavy to function properly in grinding up the carbon and coke produced in cracking and a sufficient number should be used to give intimate rolling contact with each other and the full length 65 of the bottom of the drum. As the drum is rotated with the metal balls 30 arranged in the manner indicated the walls of the drum are kept free from any coke deposit and therefore the full capacity of the chamber is always in use.

70 The rotation of the drum may be either continuous in one direction or oscillating. The oscillating motion may be progressive, that is, a rotation first in one direction through a definite angle then in the other direction through a lesser or greater angle so that eventually a com-

plete rotation is made. The drum may also be rotated at any reasonable speed but usually a very slow rotation is sufficient to maintain the carbon in suspension and prevent coking on the walls. In fact an intermittent rotation of say 80 one or two days a week or two or three hours a day is sufficient in many cases. Under present cracking methods in use by some refiners it is necessary to shut down about every twenty 85 days to remove carbon; with others the operating time is only a few days. If the apparatus described above is operated so that the drum 18 is rotated for one day each week the carbon accumulation can be completely removed without the necessity of ever shutting down except for other causes such as inspection or repairs. The rate of rotation or the frequency of the periods of rotation will of course depend to some extent on the temperatures and pressures used in the cracking apparatus or with the relative amount of unvaporized oil in the system which may if found desirable be all withdrawn by 90 pipe 78.

If the intermittent rotation of the drum 18 is practised the valve in pipe 76 may be closed 100 during rotation and that in pipe 78 left open so that the carbon being removed from the balls 30 and walls of the chamber will be more rapidly washed out. During such a period the valve in pipe 84 may be open in order to increase the 105 amount and therefore the fluidity of the oil put through the drum 18. The connection between pipe 84 and 16 is preferably of the aspirator or ejector type so that the flow of the fluids in pipe 16 will draw vapors from the pipe 84. Such connections are common and therefore not shown.

When continuous rotation of the reaction chamber is practised the intake end of the pipe 76 may be screened if it is found that too much carbon is being withdrawn by this pipe due to 115 the agitation in chamber 18.

In order to avoid contamination and stoppage with carbon of the dephlegmating and rectifying part of the apparatus it is an object of the present invention to restrict the cracking operation to the pipe still furnace 14 and the drum 18. Since the oil and vapors leaving the cracking chamber by pipes 76 and 32 are considerably above the cracking temperature provision is made for their cooling by the use of a relatively cool 120 oil from the spray 36 and the vaporization produced by the stripping operation in the lower part of chamber 34. If a crude oil is being used as a charging stock it may be completely topped of 125 gasoline hydrocarbons by being all passed through the distributor 36 in which event the valve in pipe 12 would be closed and the stripped reflux delivered by pipe 56 would be introduced directly into the pipe 12 beyond the valve. In order to be sure that no cracking takes place in the 130 tower above the chamber or compartment 34 a thermostat may be placed in the outlet 40 and used to control the valve in pipe 38 so that the quantity of cooling fluid will be governed by the outlet temperature. This will also tend to give 135 a constant performance by the rectifying tower and therefore more uniform products.

The rotary cracking chamber 18 may be used in a considerably different manner to that described above by providing two such chambers 145 so arranged that one may be cut out of the system when the other is in use. If this is done the stuffing boxes are preferably substituted by flanges and no grinding elements will be placed in the chamber in circuit. When a reaction

chamber has been in circuit for some time and has accumulated considerable carbon it is cut out and another cut in by a proper valve system. The one out of use is unbolted from the connecting pipes and either rotated in place or rolled on rails, which may take the place of the rollers 20, to a cleaning system into which it is then connected. This system will comprise a means similar to the one shown for rotating the drum 18 together with oil storage and a carbon filter or separator. After the drum to be cleaned of carbon is placed in the cleaning circuit a number of balls similar to the balls 30 are run into it and the drum rotated to pound up and free the carbon and coke collected therein. During rotation a stream of oil or water is run from a storage tank through the drum to carry out the pulverized carbon and coke which is continuously separated from the oil in any convenient manner such as by means of a thickener. The oil is used over and over for this purpose. The use of two cracking chambers with one always in circuit gives ample time for the one out of circuit to be cooled, cleaned and replaced while the other is collecting carbon, coke, etc. In the above operation it is understood that either or both of the withdrawal lines 76 or 78 may be used as long as possible to withdraw oil and/or oil with carbon in suspension. The above described method of cleaning a reaction drum may of course be used where only one drum is available in the cracking unit.

The efficiency of the process is greatly increased by the use of the stripping chambers or stills 80, 34 and that above the partition 42, by which all gasoline hydrocarbons are removed from the oil either before it is reintroduced into the heating tubes or discharged as residuum. Furthermore since the charging stock is to contain no gasoline hydrocarbons or is to be freed of such, a larger percentage will be cracked to gasoline in accordance with the "law of mass action." Upon the same principle the introduction of the non-condensed gases from the system into the charging oil tends to prevent the formation of such gases during the cracking of the oil. If crude is being topped as referred to above, gas from pipe 74 may be introduced directly into the line 12 beyond the valve. For the same reason that non-condensed gases are passed with the charging stock they are preferably heated and used in the chamber 80 if vapors therefrom are put in the line 16.

The cracking apparatus may be maintained under any desirable pressure consistent with the proper safety factors for the materials of construction, but ordinarily from 150 to 300 pounds per square inch is sufficient. Certain parts of the apparatus may be maintained under different pressures than other parts (such as a progressive reduction) by the proper manipulation of the valves in pipes 16, 32, 76, 58 and 62. The booster 72 may be used to create a sub-atmospheric pressure in the condenser 60 and the tower 6 if desired.

Under certain operating conditions it may be desirable to use a plurality of "ball mill" chambers in series in order to effect the desired cracking of the oil or to give additional cracking capacity.

In order to prevent corrosion and carbonization of the steel of which the apparatus (including the balls 30) is constructed, it may be lined in part or throughout with such metals as tin, chromium or aluminum.

The various parts of the apparatus which would be exposed to radiation losses are preferably covered with insulation. Besides having a coat of insulation on the chamber 18, it is also preferably set in a housing constructed or lined with insulating materials so as to cut down the heat loss. These various features are not shown in the drawing in order to avoid complicating the same.

It is understood that the metal balls 30 may be substituted by elements having other shapes or rods, etc., without departing from the spirit and scope of the invention, the broad aspect being the employment of such loose elements as will free the carbon from themselves and the walls of the chamber and/or pulverize the same therein.

Various other features of construction and operation may be resorted to without departing from the spirit and scope of the present invention, such for example as not returning any part of the residuum from the cracking chamber to the heater, using a by-pass around the chamber 18 to the chamber 34 for a portion of the oil from the heater 14 or constructing the reaction chamber 18 with other than a circular cross section. It may be made polygonal for example.

Having thus described the preferred form of the invention, what is claimed as new is:

1. An apparatus for distilling oils comprising an unheated rotatable cracking still, a plurality of metal balls in said still, a cooling chamber, means for passing vapors from said still to said chamber, means for spraying oil into said chamber to cool said vapors, a fractionating tower, means for conducting vapors from said chamber into said tower, means to rotate said still and means for heating oil from said chamber and for conducting the heated oil into said still.

2. The process of cracking oil in a heating coil and in a rotatable externally unheated reaction drum containing freely-moving, loose abrading elements, which comprises passing oil through the heating coil and directly into the drum, heating the oil to a cracking temperature in said coil, rotating said drum to cause the loosening and grinding by said elements of the residue produced from cracking said oil, and withdrawing from said drum the products of the cracking reaction while the drum is in rotation.

3. The process of cracking hydrocarbon oils for the production of gasoline-like products, which comprises passing the oil in a confined stream under superatmospheric pressure through a heating zone in which the oil is heated to a cracking temperature, passing the highly heated oil products from said zone into a body of oil maintained in an enlarged unheated chamber containing a plurality of abrading elements, maintaining a pressure in said chamber sufficiently low to permit substantial vaporization of liquid oil constituents introduced thereinto, rotating said chamber to prevent deposition of carbon or coke and to remove any coke deposited on the walls thereof, withdrawing oil residue from said chamber, conducting oil vapors from said chamber into a dephlegmating zone and subjecting the vaporized oil constituents to dephlegmating conditions in said dephlegmating zone, to separate the gasoline-like materials from higher boiling vapors.

4. In the process of cracking mineral oils for the production of gasoline-like products there-

from, in which a body of oil is maintained under cracking conditions of temperature and pressure in an externally unheated rotatable cracking chamber containing a plurality of loose metallic abrading elements, the improvement which comprises rotating said chamber, causing substantial vaporization of the oil in said chamber, conducting vapors from said chamber to a fractional condensing zone wherein a reflux condensate is produced suitable for cracking, heating reflux condensate from said zone to cracking temperature, and passing the products resulting from the heating of said reflux condensate while at a high temperature into said rotatable cracking chamber.

15. In the process of cracking mineral oils for the production of lower boiling point products therefrom in which a mixture of oil and gas is passed through a heating zone in which the mixture is heated to the cracking temperature of the oil and the resulting products from said heating introduced into a body of oil maintained at a cracking temperature in an externally unheated rotatable cracking still containing a plurality of relatively heavy abrading elements, the improvement which comprises rotating said still to prevent the formation of coke on the still walls by the cracking of the oil, withdrawing the vapors from said still to a fractionating zone and withdrawing residuum containing any free carbon formed in the cracking operation from said still.

20. The process of distilling oils in a rotatable vaporizing chamber to which no external heat is applied and which contains a plurality of loose abrading elements of greater specific gravity than the oil to be distilled, which comprises subjecting a body of oil in said chamber to a distilling temperature sufficient to vaporize substantial portions of the oil, passing the vapors evolved from the oil in said chamber into a cooling chamber, distributing oil to be distilled into the vapors in said cool-

ing chamber whereby said oil is topped and said vapors cooled, passing the resulting cooled vapors into a rectifying zone and passing the topped oil through a heating zone and into the body of oil undergoing distillation in said vaporizing chamber.

25. The process of cracking oil in a heating coil and in a rotatable externally unheated reaction drum containing freely-moving loose abrading elements which comprise passing oil through the heating coil and directly therefrom into the drum, heating the oil to a cracking temperature in the said coil, rotating said drum to cause the loosening and grinding of said elements of the residue produced in cracking said oil, withdrawing the vapors produced in the cracking operation from said drum during the rotation thereof and conducting them into a fractionating zone, and immediately cooling the vapors withdrawn from said drum to a temperature below the cracking temperature by contacting them with a cooling fluid prior to their fractionation in said fractionating zone.

30. The process defined by claim 3 in which the vapors conducted from said chamber into the dephlegmating zone are brought into intimate contact with a relatively cooler oil whereby the temperature of the vapors is reduced below the cracking point thereof.

35. The process defined by claim 4 in which the vapors conducted from said chamber to said fractional condensing zone are cooled to a temperature below that at which further cracking takes place by contacting therewith a relatively cool fluid.

40. The process defined by claim 2 in which products of the cracking reaction withdrawn from said drum are immediately cooled below the cracking temperature by mixing them with a relatively cool fluid.
